United States Patent Office.

WILLIAM C. LESSTER, OF NEW YORK, N. Y.

Letters Patent No. 61,623, dated January 29, 1867.

IMPROVEMENT IN FIRE-PLACE HEATERS.

The Schedule referred to in these Letters Patent and making part of the same.

TO ALL WHOM IT MAY CONCERN:

Be it known that I, WILLIAM C. LESSTER, of the city, county, and State of New York, have invented a certain new and useful Improvement on Fire-Place Heaters, of which the following is a full, clear, and exact description, reference being had to the accompanying drawing, forming part of this specification, and in which—

Figure 1 represents a transverse sectional elevation of a fire-place heater constructed according to my improvement; and

Figure 2. a horizontal section thereof, taken a little above the fire-pot.

Like letters of reference indicate like parts in both figures.

The nature of my invention consists in a peculiar construction of the fire-pot when made up in sections of cast-iron rings, by combining therewith a loose cap or flange, whereby escape of gas at the joints is restrained and every freedom given for expansion and contraction.

For the information of others whom it may concern, I proceed to describe my invention with reference to the accompanying drawing, omitting, for the most part, description of such parts as are common to other fireplace heaters.

place heaters. A, in the drawing, represents the base of the heater, the top plate of which may have an upwardly projecting ledge, *a*, to serve as a guide or steadyng rim to the fire-pot B, or, rather, the lower section of the same. This fire-pot is made up of cast-iron rings, not simply mounted one upon the other, bolted to the structure as in certain other heaters, but these rings, *b*, are each constructed at their tops by groove or channel, *c*, so as to receive freely within it the lower edge of the next ring immediately above it, thereby giving stability to the whole, with separate freedom for expansion and contraction, or detachment in case of removal and necessary repair, and a lack by the dust gathering in the groove, *c*, of each, against escape of obnoxious gases through the joints formed by the sections into the chamber or space, C, in front of and partially surrounding the fire-pot, and which has its outer shell of open-work construction to allow of the heat radiating from the fire-pot passing therethrough. To further secure the heater in this respect, without restricting the expansion or contraction of the fire-pot, the latter is provided at its top with an independent cap or flange, D, of like annular form with the rings *b*, but lapping over or loosely resting on the guide or partition-plate *d* of the heater, and by a downwardly projecting ledge or rim, *e*, fitting loosely into the groove *c* of the top ring, which groove may be faced in or closed on both sides, and in collecting dust will, by the aid of the rim *e* of the cap, seal the fire-pot joint at top without restraining the rings composing the latter from expanding or contracting, either separately or unitedly, with freedom from all strain of the fire-pot on either its base or the partition-plate *d*. To aid the combustion of the gases rising from the fire-pot into the chamber E above it, I arrange round the lower interior of said chamber an ordinary or any suitable perforated distributing pipe, *f*, to admit oxygen, which, commingling with said gases, effects, as well understood, the desired result. But, instead of supplying said distributor with air, as usual, from the outside or front portion of the heater, I arrange the perforated supply pipe *g* in rear thereof, and within the recess in the wall into which the heater is set, by which arrangement the supply pipe is not only concealed from view and damage, but is also protected against having its inlets choked either through malice, accident, or even ignorance. It not being necessary here to describe other parts of the heater represented in the accompanying drawing, I will only remark that heat generated by it may be conveyed therefrom to adjoining or upper chambers, in the usual or any suitable way.

What I claim herein as new and useful, and desire to secure by Letters Patent, is—

The combination, with the fire-pot B, made up of rings mounted upon and fitting one within the other as described, of the loose flange or cap D, constructed to enter a groove in the top ring and resting on or lapping over the partition-plate d of the heater, essentially as and for the purpose or purposes herein set forth.

W. C. LESSTER.
